Southgate Laundry.

UNITED STATES PATENT OFFICE.

WILLIAM C. SCHRENKEISEN, OF MOUNT VERNON, NEW YORK, ASSIGNOR TO HILL
LAUNDRY EQUIPMENT CO., INC., OF LONG ISLAND CITY, NEW YORK, A CORPORA-
TION OF NEW YORK.

LAUNDRY DRIER.

Application filed June 14, 1926. Serial No. 115,850.

This invention relates to a drier for use in homes and especially apartment houses for drying clothing.

The principal objects of the invention are 5 to provide a direct, untrapped, course for the damp air that collects at the bottom of a drying cabinet of this kind and direct it in a course that is always inclined upwardly, or at least level, to the fire box for the purpose 10 of evaporating the moisture in this air and reheating it and delivering it outside the drier; and to so arranged the same that it cannot become trapped and fail to provide air to the burners.

15 This is an improvement over the patent to Belding and Heldman issued March 7, 1905, No. 784,026, and involves the use of a gas radiator connected as stated above and employing several of the principles of said patent. Other objects and advantages of the 20 invention will appear hereinafter.

Reference is to be had to the accompanying drawing which is a perspective view of a drying cabinet partly broken away to 25 show the features of this invention.

I use the ordinary cabinet 10 in which the clothing is hung on sliding racks 11, as is well known in this art. At the bottom, and preferably at the front, is a fire box 12 30 heated by gas burners 13 and having a longitudinal opening 14 at the top and a narrow longitudinal opening 15 at the bottom of the rear wall. The air in the fire box is conducted directly from the opening 14 to a 35 duct 16 extending across the cabinet near, but above, the bottom at the front. This duct is connected by a series of flues 17, which preferably are horizontal and straight, to discharge into a transverse duct 40 18 at the rear. This duct discharges at the end through an outlet, either into the outer air, or up through a pipe 20 to a flue in the building.

It will be observed that the fumes pass 45 through these flues and ducts without any chance of escape into the air of the chamber or cabinet 10. In other words the clothing is heated entirely by radiation, as in said patent. I have preserved that feature.

50 Now it will be understood that the air which enters the cabinet comes in independently of the heating system, in any desired way, and that the heated air necessarily rises

and expands and forces down the cold and moist air which has been in circulation through the damp clothing above. This cold air necessarily collects at the bottom. For the purpose of taking it out of the cabinet and supplying oxygen to the burners, I provide a damp air intake 21 located along or near the floor of the cabinet. This is inclined upwardly through part or all of its length and never downwardly. It is connected with the opening 15 and on account of the draft created by the burners, it is drawn into the fire box, reheated, deprived of its moisture, and the products of combustion or fumes led out through the ducts and flues and discharged from the cabinet at the outlet 19. In other words this damp air is not in any way in danger of being trapped on its way to the fire box, which in case of a defective flue might choke the whole radiator and smother the gas because it would not get the necessary air for combustion.

It will be seen that, as in the above patent, I still bring the foul damp air from the cabinet back to the fire box and consume it. This radiator will operate perfectly without any flue connection.

The improvement over the said patent consists largely in the fact that the air is drawn into the fire box directly from the floor and also in the fact that there is no change in the direction of flow of the damp air to the fire box which might form a trap in the case of a defective flue in the building. This constitutes an important improvement, particularly in the cases in which the flue is not large enough and in which there is no flue in the building to receive the products of combustion from the outlet 19.

Although I have illustrated and described only a single form of the invention and shown it as applied to a particular form of laundry cabinet, I am aware of the fact that modifications can be made therein by any person skilled in the art and that it can be applied to other types of drying cabinets, without departing from the scope of the invention as expressed in the claims. Therefore, I do not wish to be limited in these respects, but what I do claim is:

1. In a laundry drier, the combination with a gas heated fire box, cross ducts at the

front and rear, into the front one of which the box delivers the fumes and a series of horizontal flues connecting the two ducts and conducting the fumes from one to the other, of a damp air intake having its inlet near the floor of the drier under the flues and conducting the damp air from the bottom of the drier near the center thereof into the fire box below the burners therein and below

10 one of said cross ducts.

2. In a laundry drier, the combination with a fire box at the front, ducts at the front and rear, into the front one of which the fire box delivers the fumes, and flues 15 connecting the two ducts, of a damp air intake having its inlet near the center of the floor of the drier extending under the front

duct and discharging the damp air into the fire box.

3. In a laundry drier, the combination 20 with a cabinet, of a fire box near the bottom thereof, means for conducting the fumes and products of combustion away from the fire box substantially horizontally and discharging them out of the cabinet, and an intake extending across the bottom of the cabinet 25 at a distance from the fire box for collecting the damp air and leading it substantially horizontally into the bottom of the fire box, for the purpose described.

30 In testimony whereof I have hereunto affixed my signature.

WILLIAM C. SCHRENKEISEN.
